CLAIM

The ornamental design for a portable intraoral scanning device as shown and described.

DESCRIPTION

FIG. 1 is a front left perspective view of a portable intraoral scanning device with the handle in a first position in accordance with the claimed design.

FIG. 2 is a rear left perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is a rear left perspective view of a portable intraoral scanning device with the handle in a second position in accordance with the claimed design.

FIG. 10 is a front view thereof.

FIG. 11 is a rear view thereof.

FIG. 12 is a right side view thereof.

FIG. 13 is a left side view thereof.

FIG. 14 is a top view thereof; and,

FIG. 15 is a bottom view thereof.

The broken lines in the figures show portions of the portable intraoral scanning device that form no part of the claimed design.

1 Claim, 13 Drawing Sheets
